(57) **CLAIM**

The ornamental design for a retention spoon, as shown and described.

DESCRIPTION

FIG. 1 is a top-front-perspective view of a retention spoon showing my new design; thereof;

FIG. 2 is a side perspective view thereof;

FIG. 3 is an end perspective view thereof; and,

FIG. 4 is a bottom plan view thereof.

The broken line showing of a spoon handle in FIGS. 1-4 is included for the purpose of illustrating environmental structure and forms no part of the claimed design.
